UNITED STATES PATENT OFFICE

JOHN W. KELLY, OF ERIE, PENNSYLVANIA

ILLUMINATED SIGN

Application filed September 26, 1929. Serial No. 395,339.

This invention has to do with signs illuminated by artificial light, and one of the primary objects in view is that of providing a sign wherein a line of light constitutes the sole light source for illuminating a sign. It is to be appreciated that with signs employing a line or point of light, only a portion of the sign is illuminated insofar as the eye of the observer is concerned, or at most certain portions of the sign are illuminated to a greater extent than others, so that the resultant effect is anything but pleasing and efficient. Especially is this true in the case of signs which depend for their visibility on their translucence or transparency, wherein the sign is positioned between the source of light and the observer.

It is therefore a primary consideration in putting my invention into operation, to provide means between the line source of light and the observer to spread out and uniformly diffuse the light emanating from the source over an area of considerable extent, the exact extent of course depending on the dimensions of the sign. To this end I provide a glass plate having a plurality of ribs parallel to each other and dispose, adjacent to the plate, a source of light, in the form, for example, of an incandescent lamp having an elongated filament, in which example the plate is positioned with the ribs thereof parallel to the filament. I have found by experience that there is no spreading out of the light when the ribs are normal to the filament and that when they are parallel thereto the spreading is at a maximum. At all angles between the two positions just mentioned the spreading effect varies between the two extremes mentioned. I have found also that the ribs, while having the desired spreading effect above outlined, present the defect that they show up a plurality of regions of alternating high and low light intensity. To obviate this feature and present a substantially uniform area of light, I provide, either by a separate piece of glass or on the same glass but on the side opposite to the ribs, a stippled, mottled or beaded effect. I have found that this mottling or stippling has the desired effect, namely, of further refracting and uniformly

diffusing the light passing through the plate, thus assuring uniform illumination of the character of the sign by overcoming the tendency of the ribs to produce the aforementioned regions of varying intensities.

For a full and more complete understanding of the invention reference may be had to the following description and accompanying drawings, wherein—

Figure 1 is a view in elevation of a sign to be illuminated in accordance with my invention.

Figure 2 is a vertical cross sectional view showing the detailed construction, taken on the line 2—2 of Figure 1, certain of the parts being shown in elevation.

Figure 3 is a horizontal sectional view taken on the line 3—3 of Figure 2.

Figure 4 represents a modified form of the invention, wherein the sign is obliquely disposed with respect to the light diffusing screen and source of light, the light being reflected from the sign to the observer instead of being transmitted to the observer through the characters of the sign.

Figure 5 is a fragmentary view in elevation of another form of sign constructed in accordance with the present invention and which is adapted for use in accordance with the arrangement illustrated in Figure 4.

Referring to the drawings, the surface of the sign A, as illustrated, is formed of transparent or translucent letters stenciled in an opaque field. Of course whether the letters are in fact stenciled or otherwise formed is of no materiality so long as light encounters no difficulty in passing therethrough. An incandescent lamp 2 having an elongated filament 3 constituting an elongated source of light is connected to a suitable socket 4 which is connected to a source of electricity by means of wiring 5. This source of light is substantially the height dimension of the sign. Disposed intermediate lamp 2 and the sign A is a plate 6 of translucent or transparent glass having a ribbed surface 7 facing the lamp 2 and a mottled or beaded surface 8 facing the sign A. A casing or box B encloses the apparatus and is provided with a flange 9 cooperating with channel 10, form-

ing a guideway and pocket for the sign A. Disposed on the other side of the plate 6 is a flange 11 which cooperates with the channel 10 to form a guideway and pocket for the plate 6. The casing has a removable top 12 and the sign A and plate 6 are slidable into and out of position. With the filament 3 of the lamp 2 illustrated, a pencil-like beam of light is presented at the plate 6 and is spread over a considerable area. The light passing through the body of the plate 6 consists of alternating regions of high and low intensities of illumination. The rough surface 8 spreads the regions of greater luminosity over those of less luminosity so that the light reaching the sign A is of substantially uniform intensity throughout its area. Thus the light reaching and passing through the sign A covers an area sufficient to render the whole of the sign visible to the observer and all parts of the sign are illuminated to substantially the same degree.

While in the preferred embodiment of my invention the rib portion 7 faces the light source and the roughened or mottled portion 8 faces the sign, a similar effect may be obtained by reversing the positions of these surfaces. Moreover, I consider it within the scope of my invention to place the sign A between the lamp 3 and the plate 6, if so desired. While I have illustrated a single lamp, it is to be understood that a plurality of lamps in substantially parallel relation may be provided in order to present a light of greater intensity or uniformity, or both, these lamps extending preferably in a plane substantially parallel to the plate 6. Of course the intensity of light may be varied by using various lamps. The ribs 7 may have a contour other than that shown in Figure 3, obviously the intensity of the light passing through the sign may be varied by varying the relation of the parts of the device; for example, by positioning the lamp closer to the sign, greater luminosity at the sign results.

I have found that the spreading effect produced by the plate for a given light source intensity is dependent, among other things, on the size and number of ribs in a given length. Accordingly, the effect can be varied by arranging the parts to suit the need or desire. Moreover, the desired colored effect may be obtained in any one of numerous ways as by providing a lamp whose glass is colored, or by coloring the light spreading plate, or the characters composing the sign.

My novel device is capable of arrangement for display purposes wherein light from the source, instead of passing through the sign, as described hereinabove, is reflected from the sign. In such an event, the light source and the spreading or diffusing plate and the observer may be on the same side of the sign. The sign in such an arrangement would pref-

erably be of a highly reflective nature, through, of course, the intensity of reflected light will depend also on the intensity of the light source, the spreading or diffusing medium, and the arrangement of the parts.

70

In Figure 4 I have shown such an arrangement. In this modification I provide a lamp 2 and space therefrom a plate 6 provided with a ribbed portion 7 and stippled or roughened portion 8, the ribs 7 being substantially parallel to the lamp 2. Disposed at an angle to the plate 6 is a reflecting sign C having the characters or letters 12 thereof mirrored as by silvering, the remainder 13 of the sign constituting the field upon which the sign characters are carried, being covered as by paint, the letters being highly light-reflecting while the field is light absorbing. The pencil of light at the lamp 2 after passing plate 6 is spread out into a considerable area by the ribs 7 and the shadows formed by said ribs are overcome by the stippled or roughened surface 8 as heretofore described so that all parts of the letters forming the characters of the sign receive substantially the same amount of light which is reflected outwardly due to the angularity of the sign C so that it may be seen by an observer. If I so desire, I may interpose a sign such as A in Figures 1, 2, and 3 between the plates 6 and C. In such event the light will pass through the sign A just as it does as illustrated in Figures 2 and 3 and the light after passing the sign A will take the form of the letters in the sign A and will be projected toward C and reflected from C to the observer. In this case C would be entirely silvered.

100

105

It is to be distinctly understood that the invention is not limited to an incandescent lamp as a light source, but that any unitary or local source of light such as is furnished by gas or other substance may be employed.

Having thus described my invention, what I claim as new and desire to secure by Letters Patent of the United States, is—

110

1. In an illuminated display of the class described, a sign, a lamp adapted to project a pencil beam of light toward said sign, a plate extending substantially parallel to said sign intermediate the latter and the source of light and provided with means for spreading the pencil beam to an area corresponding in size to that of the sign, said means comprising spreading means on one surface of the plate and diffusing means for uniformly diffusing the spread light in all directions on the opposite surface.

115

2. The method of producing uniform illumination of an object which comprises projecting a pencil beam of light from an elongated source of illumination directly toward the object, dispersing the said pencil beam over a substantial region of an area substantially that of the object, uniformly intensifying and dispersing the light in all directions,

120

125

130

and subjecting the object to be illuminated to the thus uniformly intensified and dispersed light.

3. The method of illuminating a sign which consists in projecting a pencil beam of light from an elongated source directly toward the sign, spreading the light by refraction to an area corresponding to the area of the sign to be illuminated, and uniformly intensifying and dispersing the area of light in all directions to substantially eliminate variations in the light intensity, whereby all parts of the sign will be substantially uniformly illuminated.

4. The method illuminating a sign which comprises subjecting the sign to a pencil beam of light emanating from an elongated source corresponding in dimension to one dimension of the sign to be illuminated, spreading the beam so as to cover an area substantially corresponding to the other dimension of the sign, and then uniformly intensifying and dispersing the said beam so as to produce uniformity of illumination over the sign area.

5. A device for producing uniform illumination comprising the combination with an object to be illuminated, of an elongated source of light, transparent means for uniformly diffusing in all directions by refraction the rays of light emanating from the source to produce thereby a region of uniform intensity of light at the object to be illuminated, and means for intensifying and uniformly dispersing the diffused light.

6. A device for producing uniform illumination comprising the combination with an object to be illuminated, of an elongated source of light, and a light transmitting plate having ribs on one surface to first diffuse the beams of light emanating from the source and having beads on the other surface to uniformly intensify and disperse in all directions the light so diffused and transmitted through the plate.

7. In an illuminated display of the class described, a sign, a cylindrical elongated source of light to project a pencil-like beam toward the sign, and a light transmitting plate extending substantially parallel to the sign and having ribs on one side of the plate for spreading the pencil beam to an area of light corresponding in size to that of the sign.

8. In an illuminated display of the class described, a sign, a lamp of elongated tubular form for projecting a pencil beam of light toward the said sign, and means for diffusing the light over an area of substantially uniform intensity whereby all parts of the sign will be substantially uniformly illuminated, the said means including a transparent member having a beaded surface on one side and a ribbed surface on the other side of the transparent member, the ribbed surface facing the light source and spreading the light

from the source uniformly over the area of the sign.

9. In an illuminated display of the class described, a sign, a tubular lamp having an elongated filament for projecting a pencil beam of light toward the sign, a device extending substantially parallel to the sign and intermediate the same and the source of light, the device having means on one side for spreading the pencil beam of light to an area of light corresponding in size to that of the sign, the means comprising ribs arranged substantially parallel to the light source, and means on the other side for uniformly intensifying and dispersing the light, the means including a beaded surface on the device, the beaded surface receiving the spread light by transmission through the device.

10. As a new article of manufacture, a light refracting member having on one surface a plurality of parallel ribs and light intensifying and dispersing means on the opposite surface, the said intensifying and dispersing means comprising a series of bead-like projections having spherical surfaces, the projections being in substantially uniform contact with each other.

11. In an illuminated display of the class described, a sign, an elongated lamp for projecting a pencil-like beam towards the said sign, a device extending substantially parallel to the said sign and intermediate the same and a source of light, the said device being transparent and having means for spreading the said pencil-like beam of light to an area of light corresponding in size to that of the sign, the said means comprising ribs formed in one side of the device, the ribs being arranged substantially parallel to the light source.

12. As a new article of manufacture, a light transmitting plate having on one surface a plurality of parallel ribs and light intensifying and dispersing means on the opposite surface, the light intensifying and dispersing means comprising a series of bead-like projections having spherical surfaces, the projections being in substantially uniform contact with each other.

13. As a new article of manufacture, a transparent light refracting member having formed in one surface a plurality of parallel ribs, the other surface being provided with light intensifying and dispersing means opposite the ribs and comprising a plurality of transparent bead-like projections having spherical surfaces which uniformly intensify and disperse light transmitted thereto through the member from a source of light, and project the thus dispersed light upon an object to be illuminated.

14. In an illuminated display of the class described, a sign, an elongated cylindrical shaped lamp adapted to project a pencil-like beam toward the said sign, and a light trans-

mitting plate extending substantially parallel to the sign, the plate having ribs on one side for spreading the pencil beam to an area of light corresponding in size to that of the sign, the ribs extending substantially parallel to the lamp.

15. In an illuminated display of the class described, a sign, an elongated lamp for projecting a pencil beam of light toward said sign, and means for diffusing said light over an area of substantially uniform intensity of light whereby all parts of the sign will be substantially uniformly illuminated, said means including a light transmitting member having a beaded surface on one side and a ribbed surface on the other side of the transparent member, the ribbed surface facing the light source, the ribs being substantially parallel thereto.
- 10 16. An illuminated display of the class described comprising, in combination, a sign, a tubular lamp having a single elongated filament for a light source for projecting a pencil beam of light toward said sign, a device 15 extending substantially parallel to said sign and intermediate the same and the source of light, said device having means on one side for spreading the pencil beam of light in a lateral direction to an area of light corresponding in size to that of the sign, said means comprising ribs arranged substantially parallel to the said elongated light source and means on the other side for uniformly intensifying and dispersing the light in all 20 directions, said means comprising a beaded surface on the device, the beaded surface receiving the laterally spread light by transmission through the said device.

In testimony whereof I affix my signature.

JOHN W. KELLY.
